23 Claims. (Cl. 123—69)

This invention relates to improvements in internal combustion engines and particularly it relates to two-cycle engines and methods of operating the same.

Heretofore engines of the two-cycle Diesel, semi-Diesel or low compression type have employed numerous and heavy auxiliaries, such as apparatus for compressing combustion air, fuel injecting means, means for scavenging exhaust gases from the working cylinder and the like, all of which resulted in such excessive weight in pounds per horsepower developed by the engine that Diesel, semi-Diesel as well as low compression engines have been rendered impractical for use on airplanes, automobiles, and the like. Usually these auxiliaries have been disposed in spaced relation to the engine and separated by pipes and conduits from the working cylinder of the engines further adding to the weight and increasing to a maximum the space necessary for engine installation. Therefore, an object of this invention is to eliminate these objections by providing a two-cycle engine having novel and efficient auxiliaries such as scavenging air pumps, fuel injection pumps and the like which enables the engine to be mounted on a support in such a manner that it occupies but a minimum space and may accordingly be adaptable for use on airplanes, automobiles, boats, or the like by virtue of the minimum weight of the engine in pounds per horsepower developed and which will also effect a considerable decrease in fuel consumption per horsepower developed under varying loads.

Another object of this invention is to provide an engine of the type herein referred to characterized in having the parts comprising the same so arranged as to dispose substantially all of the auxiliaries within the axial confines of the engine cylinder walls.

Another object of this invention resides in the provision of an improved method and means for scavenging exhaust gases from two-cycle engines either of the high compression selfignition type or the type relying on electric or other means of ignition.

Another object of this invention is to provide a novel method and means for efficiently and readily mixing and highly vaporizing a rich charge of either high or low grade fuel and injecting the mixture into the working cylinder of the engine.

Another object of this invention resides in a method and means for forming a mixture rich in combustible matter, such as heavy oil in air, ex-

panding the same in a partial vacuum, then in compressing and heating it to highly vaporize the mixture, introducing and atomizing the mixture into highly compressed combustion air in the working cylinder of the engine to cause 5 thorough intermixture therewith and complete combustion of the fuel and operation of the engine, and finally scavenging the spent gases from such combustion.

Another object of this invention resides in a 10 method and means for forming a carbureted mixture of gasoline, kerosene, or the like fuel, expanding the same in a partial vacuum, then in compressing and heating it to vaporize the mixture, introducing the mixture into the combustion 15 chamber of a power cylinder, igniting said fuel mixture to cause operation of the engine, and finally scavenging the spent gases from the combustion cylinder.

Another object of this invention is to provide 20 an improved method and means which enables the volume and pressure of scavenging air to be readily varied in accordance with volume of fuel mixture to be compressed and introduced into the power cylinder.

Another object of this invention is to provide 25 an improved fuel injection and exhaust gas scavenging means for two-cycle engines which is of extreme light weight, simple and durable in construction and composed of a minimum number of moving parts, and which may be economically manufactured.

Other objects of the invention will appear as 30 the description thereof proceeds.

The invention is capable of receiving a variety 35 of mechanical expressions, one of which is shown in the accompanying drawings, but it is to be expressly understood that the drawings are for purposes of illustration only and are not to be construed as a definition of the limits of the invention reference being had to the appended 40 claims for that purpose.

Figure 15 is an enlarged sectional view of one form of fuel injecting nozzle employed.

Referring more in detail to the embodiment of the invention illustrated in Figures 1, 2, and 9, reference numeral 1 indicates an engine working cylinder having a piston 2 mounted for reciprocation therein. The piston 2 is suitably connected to the crank shaft 3 by a connecting rod 4 for converting and transmitting reciprocatory movement developed in the working cylinder into rotary movement of the crank shaft. Crank shaft 3 is supported for rotation in bearings 5 disposed in the crank case A, and a pair of cams 6 and 7 are carried by the crank shaft adjacent the bearings 5.

The engine cylinder block 17 is preferably substantially rectangular in cross section and is provided with a water jacket B surrounding the working cylinder 1 while the upper end is provided with an axially extending aligned closed portion 18 for housing the scavenging air pump and fuel injecting pump which will be herein-after referred to in detail.

Associated with the cams 6 and 7 are preferably a pair of vertically disposed rods 8 and 9 carrying a pair of cam eccentrics 10 and 11, respectively, which surround cams 6 and 7, respectively, which reciprocate the rods vertically when the crank shaft is rotated. Aligned bearing sleeves 12 are mounted in suitable bores in the upper and lower water jacket partition walls 13 and provide guides for the vertically reciprocable rods 8 and 9. The upper ends of the rods 8 and 9 are secured by nuts or other suitable means 14 to an annular flange 15 carried by a double acting piston generally indicated at 16 which piston is mounted for reciprocation in a cylindrical scavenging air suction and compression chamber 20 formed in the housing 18.

Piston 16 preferably comprises an enlarged upper cylindrical portion 19 slidably mounted in the chamber 20, and a downwardly depending piston portion 21 thereof is reciprocably mounted in a relatively small cylindrical fuel mixing chamber 22 formed on an annular upwardly extending portion of the cylinder top wall 23.

Each of the pistons 19 and 21 is provided with circumferential grooves 24 and 25, respectively, for the reception of suitable high fluid pressure sealing rings to reduce escape of fluid pressure from chambers 20 and 22 to a minimum. The lower end of the chamber 22 is normally closed off from the working cylinder 1 by an annular plug 35. This plug has a small passage 31 there-

through which terminates in an annular groove 31' through which fuel is forced by the piston 21 under high pressure on its descent in the chamber 22, to the combustion chamber C in the working cylinder of the engine. Plug 35 also provides a support for a disk valve 26 covering said groove, the stem 27 of which is guided in a bore in said plug, and is provided with a head 29 movable in an enlarged annular recess also in the plug. An expansion spring 30 is compressed between the valve stem head 29 and the lower wall of the plug recess and normally retains the valve in a position as shown in Figure 1 covering the groove 31' and cutting off the flow of fuel from chamber 22 to the combustion chamber of the 15

A rich mixture is sucked into the chamber 22 by virtue of the vacuum created by the piston 21 on its ascent through an aperture 32 having communication through a pipe 33 with a source 20 of fuel such as heavy fuel oil where engine is run on Diesel or semi-Diesel principle and gasoline or kerosene when engine is exploded by electric ignition. At the same time, air is drawn into the pipe 33 by the suction action of the piston 21 and mixes with said fuel in chamber 22. A throttle valve 110 is preferably interposed between the source of air and fuel and the mixing chamber 22 to regulate the amount of fuel supplied to the engine to control the engine speed 30 with facility, through a rod or the like 111. During the descent of the piston 21 fuel is first compressed and when sufficient pressure is reached in chamber 22 to overcome the pressure of combustion air in the combustion chamber, 35 the fuel mixture is forced through the passage 31, groove 31', opening the atomizing valve 26 and into the combustion chamber C wherein it is spontaneously exploded.

The fuel mixing, compressing, vaporizing, 40 atomizing and injecting method and apparatus just described are more fully disclosed in co-pending application Serial No. 256,766 filed February 28, 1928.

The chamber 20 heretofore referred to is provided with an opening 36 communicating with a downwardly extending substantially rectangular shaped air passage 37 which may be opened to the combustion chamber C through a vent 38 when the power piston is in the position shown 50 in Figures 1 and 2. An inwardly opening check valve 39 controls an opening for admitting scavenging air to chamber 20 during the suction stroke of the piston 19. During the compression stroke of the piston 19, valve 39 is closed and 55 the scavenging air thus compressed is forced into the combustion chamber C through passage 37 and vent 38, the burnt gases escaping rapidly through an outlet or exhaust vent 40 disposed in the cylinder wall 1 diametrically opposite the 60 vent 38.

The upper wall 151 of the chamber 20 is provided with a threaded opening into which a threaded plug 152 is screwed. This plug may be screwed into the chamber 20 to varying depths to 65 decrease or increase the size of chamber 20 and thereby regulate the volume of scavenging air employed. Accordingly, it is possible to regulate the volume of scavenging air desired, although the stroke of the scavenging piston 19 and injecting piston 21 is the same.

The housing 18 heretofore referred to is adapted to retain heat communicated thereto by the cylinder wall 23 and provides a preheating chamber for the fuel and scavenging air. This 75

pre-heating of the fuel and scavenging air greatly facilitates vaporization and final complete combustion of the fuel during operation of the engine. Moreover, fuel consumption is reduced to a minimum. An opening 95 may be formed in the housing 18 to permit access to the interior of the same, and may be closed by a cover plate 96.

The engine described above operates in the following manner: In the power cycle of piston 2 the injector piston 21 moves away from the piston 2 and produces first a definite vacuum in chamber 22 which vacuum sucks the rich combustible mixture supplied through opening 32 and the carburetor 33 and air pipe 34, into chamber 22. During the period of compression of the rich combustible mixture in chamber 22, the power piston 2 and the fuel injector piston 21 are brought together by the action of the crank 3, and reach maximum pressure simultaneously, moving in the direction of arrows 101 and 102, respectively. Piston 2 passes vents 38 and 40 and closes the same while the injector piston 21 compresses the rich fuel mixture sucked in through opening 32 to chamber 22, to a very high degree, which pressure is sufficient to open the valve 26 and overcome the compression pressure of the combustion air in the combustion chamber C wherein it is atomized and ignited, by the high pressure of the combustion air.

At substantially the same time the scavenging piston 19 moving in the direction of arrow 103, draws scavenging air into chamber 20 and on the next upward stroke of piston 21 forces this air by way of passage 37 into the combustion chamber C, as soon as vent 38 is opened by the moving piston 2, at the end of its stroke. This scavenging air then drives the burned gases from the cylinder 1 by way of vent 40.

Axial adjustment of the cams 6 and 7, heretofore referred to for varying the timing of the fuel injection with respect to the working piston 2 may be carried out in any manner. However, in Figures 1 and 4, one means is shown for accomplishing this adjustment comprising a plurality of radially arranged holes 130, 131 which communicate with holes 132, 133 in a cheek 135 of the crank shaft. Bolts 136 pass through these holes and secure the cams rigidly on the crank shaft. These bolts may be removed from the holes as shown with facility and the cams rotated to either of the angles illustrated by lines 137 or 138 to increase or decrease the throw of the eccentrics and accordingly the stroke of the scavenging and injector piston.

The method and the means for carrying out the invention described above assures numerous important advantages, such as the unitary control and actuation of the fuel injector piston 21 and the scavenging air piston 19; with great simplification of the method and of the parts comprising the engine.

It is of special note that the installation includes no separate air compressor, the pump for the sweepage air being in fact supplied by the combination of the sweepage piston 18 disposed in the axial confines of the engine cylinder walls, resulting in an engine which is very compact, simple and economic in construction.

Furthermore, there is obtained easily and surely the coordination of the various operations and parts comprising the means for sweeping the spent gases from the cylinders, the fuel injection and the power stroke of the engine.

As heretofore stated in the engine illustrated

in Figures 1 and 2 just described, the eccentrics 6 and 7 and their respective eccentric collars 10 and 11 for reciprocating the double acting piston 16, are preferably disposed adjacent to the crank 3, so that the same are confined within the axial limits of the cylinder wall. This arrangement is considerably advantageous in opposed cylinder, radial cylinder or V-type cylinder engines where in space is materially conserved and the weight per horsepower developed is reduced to a minimum. However, the arrangement of cams and eccentrics would result in considerable crowding of parts in engines of the plural horizontally arranged cylinders.

In order to overcome such difficulties, one means is suggested in a modified embodiment of the invention which is diagrammatically illustrated in Figure 6 of the drawings, wherein, preferably countershafts 42 and 43 are provided and may be suitably journalled in bearings, not shown, in the crank case A each in parallel relation with the crank shaft 3'. Cams 6' and 7' are mounted on the shafts 42 and 43, respectively, adjacent to sprocket wheels 45 and 46 also non-rotatably secured thereon. Crank shaft 3' is also provided with a sprocket wheel 47 disposed between the cranks of the shaft and in transverse alignment with sprocket wheels 45 and 46 and preferably of the same size. A sprocket chain 48 is disposed about the sprocket wheels 45, 46 and 47 which transmits rotation to the counter shafts 42 and 43 at crank shaft speed. It will be seen that this arrangement permits the upper run 49 of the sprocket chain to pass over the bearings of the shaft 3'. Reciprocatory motion is communicated to the vertically reciprocating rods 8' and 9' from the eccentrics 45 and 46 to reciprocate the double acting piston 16' in a manner similar to the embodiment of Figures 1 and 2. Moreover, axial crowding of the engine cylinders in horizontally disposed multiple cylinder engines is reduced to a minimum while at the same time permitting such cylinders to be disposed in as close proximity as possible in the line of assembly of the cylinders.

Referring now to the embodiment of the invention illustrated in Figures 7 and 8 a novel and modified double acting pump construction 16" and means of operating the same, is shown differing in details of construction from that illustrated and described in the foregoing embodiments of the invention, and which has given satisfactory results.

In this embodiment of the invention, the engine crank shaft 3" is preferably provided with a cam 50, non-rotatably secured thereto adjacent the crank portion of the shaft 3". This cam preferably engages a small roller or wheel 51 rotatably carried by a guide 52 which is reciprocally mounted in a bearing 53 secured in a bore in the engine crank case wall. A stem 54 is carried by the guide 52 and is preferably provided with a ball shaped head which engages in a complementary ball socket joint recess 54' in the lower end of a transmission rod 55 and provides a driving connection between the guide 52 and rod 55, all of which convert rotary motion of the crank shaft 3" into vertical reciprocatory motion of rod 55.

The upper end of the rod 55 is preferably formed with a ball head disposed in a complementary ball socket 56 disposed on the outer end of a transversely extending rocker arm 57, pivoted at 58 on a support 59 anchored at 60 to the cylinder wall 17'. The inner portion of the

rocker arm 57 extends through a recess 80 in the cylinder wall adjacent the pivot 58, and carries a roller 61 in a bifurcated end portion thereof. Said roller is adapted to constantly engage and 5 actuate a plate 62 carried by the double acting pump 16''. Said pump 16'' preferably comprises a fuel mixing and injecting piston portion 21' to which plate 62 is threaded at 81, and a scavenging air piston portion 63 carried by upwardly extending webs 72 preferably cast integral with the plate 62.

A fuel injecting piston 21' is mounted for reciprocation in a cylindrical sleeve 73 which rests in a recess 74 in the upper face of the cylinder head wall 75. Piston 21' and its cylinder are rendered fluid tight by suitable piston rings 89. A reduced bore portion 16 of said recess communicates with the combustion chamber C' of the cylinder 1' and receives a plug 77 which carries 20 a fuel atomizing disk valve 26' normally retained on its seat 78 by the expansion spring 79 and closes off fuel duct 27' from communication with the combustion chamber C'. A head 83 on valve stem extends upwardly into a recess 85 in the 25 plug 77 and provides an anchor for the upper end of the spring 79, the lower end of the spring being compressed against the base of the recess 85.

An annular flange 66 is formed on the sleeve 73 30 adjacent its upper end and is adapted to receive bolts 87 threaded into the cylinder head wall 75 to secure the sleeve in the recess 74 in the cylinder head wall. A coiled spring 65 is compressed between the plate 62 and the annular flange 66, 35 and normally exerts an upward pressure on the scavenging air pump piston 63 during the scavenging stroke of said piston. Piston 63 is formed with a circumferentially grooved annular depending flange 86 which engages the side walls 83 of the cylindrical scavenging air chamber 20' formed in the upper portion 17' of the cylinder block. Piston 63 is rendered fluid tight in the chamber 20' by piston rings 88 in the grooves of flange 86. As best shown in Figure 8, an opening 40 36' is formed in the chamber 20' and communicates with a passage 37' the latter of which has communication with the lower end of the combustion chamber C' in a manner such as is set forth in the embodiment illustrated in Figures 1 45 and 2 heretofore described. A bore 32' is formed in the sleeve 73 for the passage of a suitable fuel mixture from a source of fuel supply not shown.

Operation of this embodiment of the invention is substantially the same as that of Figures 1 and 55 2 in the following manner:

During the compression stroke the engine piston 2' under the impulse of the crank shaft 3'' is moved in the direction of the arrow 98, the cam 59 by means of the small wheel 51 and the transmission rod 55, causes the rocking lever 57 to oscillate around the axis 58, and roller 61 forces 60 the plate 62 of the injector piston 21' downwardly in the direction of arrow 91 compressing the spring 65 and compresses the mixture of air and combustible matter previously sucked in to chamber 73 on the suction strokes of the piston, and finally 65 injects the fuel into the combustion chamber C' in a highly atomized state and at a pressure in excess of the combustion air in the combustion chamber.

During this stroke of the power piston and fuel injecting piston, the scavenging piston 63 draws in a fresh supply of air for scavenging the combustion chamber C' as has heretofore been de- 70 scribed.

During the power stroke of the engine piston 2', the injector piston 21' ascends in the direction of arrow 93 from its point below dead center to its point above dead center and opens the vent 32' and the combustible mixture rushes into chamber 73 by virtue of the vacuum created by the suction stroke of the piston 21'.

At the same time, piston 63 compresses the scavenging air drawn into the chamber 20' during the previous stroke of the power piston which motion is produced by the expanding action of spring 65 highly compressed by the preceding engine power stroke. As a result, this motion is very abrupt, which causes the scavenging air thus compressed to completely drive out the 15 spent gases of the previous power stroke of the engine.

The cam 59 may be mounted on crank shaft 3'' so as to regulate at will the speed of fuel piston and the suction of the scavenging air. The 20 shape of the cam may be readily varied as to give very rapid movement, permitting, if desired, practically adiabatic compression.

The positive action of piston 21' and suddenness of this release of the fuel mixture facilitate 25 greatly the vaporization and atomization of the combustible mixture which is injected through duct 27' into the combustion chamber 1'.

Referring in detail to Figures 12 and 13 of the drawings a modified means is shown for regulating the amount of fuel supplied to the mixing chamber 22, for controlling the speed of the engine, and comprises a rotary plug throttle valve 120 mounted in a hollow block 121, supported by the chamber. A venture 123 provides an air intake, and fuel oil or the like being supplied through pipe 124. Preferably a needle valve 125 is pressed into pipe 124 by spring 129 and is formed with a head 126 at its opposite end which engages with a cam or wedge 127 rotatable by 40 a hand lever 128. Said wedge is disposed coaxial with the plug valve 120 and is adapted to rotate therewith when the handle is turned so that the needle valve and rotary plug open or close synchronously with the rotation of the 45 handle. Throttle valve 120 is closed almost entirely at low speeds so that the injection cylinder 22 is filled under lower pressure than when the throttle valve is wide open. The result of this is that at the time of compression in the injection 50 cylinder, the necessary pressure to open the injection valve is reached later, and therefore, there is an advance in injection at high speeds when the throttle valve 120 is wide open.

It is to be understood that the invention may 55 be applied to low pressure engines employing light fuels, such as gasoline, kerosene or the like with equal facility. In such cases a standard spark plug 100, Figure 1, may be utilized to ignite the fuel charge introduced into the engine 60 cylinder, or it may be applied to two-cycle engines having opposed cylinders, radial cylinders, horizontal cylinders, or V-type arranged cylinders with equal facility and without materially varying the essential elements constituting the 65 invention.

The invention is equally adaptable for use in two-cycle Diesel engines of the solid injection type. As best shown in Figure 14 a solid fuel oil injecting pump is shown comprising a piston 70 175 adapted to be reciprocated in a cylinder 176, by a rocker arm 57', rocked by a rod 55'. On the suction stroke of the piston fuel oil is drawn into the cylinder 176 through pipes 171. Said fuel is then injected at extremely high pressure 75

into the combustion chamber by unseating an injector valve 178 normally retained on its seat by a powerful spring 179, as the power piston reaches maximum compression. Piston 175 is connected with the scavenging pump 19' in the manner heretofore described.

The operation of all of the above described embodiments may be more readily understood by referring to Figures 10 and 11 wherein, the engine power stroke and compression stroke, together with fuel mixing and injecting action of the fuel pump, and the suction and scavenging action of the scavenging pump is diagrammatically depicted.

15 Summing up, the invention comprises an arrangement of parts so assembled as to minimize weight and which is very simple in operation, thereby effecting a considerable reduction in fuel consumption. At the same time the method of 20 operating the engine contemplates first, the simultaneous compression of air in the engine cylinder and compression of the fuel mixture in an auxiliary compression chamber, then the fuel injection and simultaneously the admission of scavenging air in the scavenging pump during this 25 cycle of operation. The next engine cycle provides the power stroke after which the scavenging air is compressed and finally forced under high pressure into the cylinder to rid the cylinder of 30 burned gases.

Each embodiment of the present invention provides an improvement in the processes for the sweeping out of the burned gases from all 35 types of two-cycle engines, as well as the fuel injecting process and apparatus, the latter of which consists in suddenly expanding a rich fuel mixture in a partial vacuum, then compressing said fuel mixture to thereby heat and vaporize the fuel content thereof, and finally injecting 40 the mixture into a chamber containing compressed air.

Moreover, it will be seen that the invention applies to sweeping out burned gases from a heat engine functioning according to the double cycle 45 characterized by causing variation of the volume of the suction chamber and by compression of the air for scavenging, which permits regulating at will the pressure of the air and accordingly its action on the burned gases of the engine.

50 While the embodiments of the invention illustrated in the drawings have been described with considerable particularity, it is to be expressly understood that the invention is not restricted thereto as the same is capable of receiving a variety of mechanical expressions some of which will now readily suggest themselves to those skilled in the art, while changes may be made in the details of construction, arrangement and proportion of parts, and some features used 55 without departing from the spirit of the invention. Reference is therefore to be had to the appended claims for a definition of the invention.

What is claimed is:

1. In a two-cycle engine the combination of 65 a working cylinder, and a double acting pump, having a pair of pump chambers and oppositely disposed piston portions working in said chambers, said pump adapted on one stroke to simultaneously suck air into one of said chambers and compress a charge of fuel in the other chamber, while on the stroke in the opposite direction the air is compressed and driven from said air chamber into the engine cylinder and simultaneously a second fuel charge is sucked into the 70 said second chamber.

2. In a two-cycle engine the combination of a working cylinder, a scavenging pump, and a fuel injection means, all disposed in axial alignment, said pumps and fuel injection means each driven by the engine and operable in opposite 5 directions.

3. In a two-cycle engine the combination of a working cylinder, a scavenging pump, and a fuel injection means, all disposed in axial alignment, said pump and fuel injection means comprising a double acting pump having oppositely disposed piston portions, and driven by the engine. 10

4. In a two-cycle internal combustion engine, the combination of a working cylinder, a power 15 piston reciprocable therein, and a scavenging pump, spaced from said piston, said pump being disposed in axial alignment with the power piston, and means responsive to the movement of the power piston for actuating the scavenging 20 pump in a direction opposite to that of the power piston.

5. In a two-cycle internal combustion engine, the combination of a working cylinder, a power 25 piston reciprocable therein a crank shaft, and a scavenging pump, said pump confined wholly within the limits of the cylinder block, and means operated by the crank shaft for compelling movement of the scavenging pump in opposition to the direction of movement of the power piston. 30

6. In a two-cycle internal combustion engine, the combination of a working cylinder, a power 35 piston reciprocable therein, and a scavenging pump, said pump confined wholly within the limits of the cylinder block, and means responsive to power piston movement for actuating the pump in timed relation with and in a direction opposite to the movement of the power piston.

7. In a two-cycle internal combustion engine, the combination of a working cylinder, a power 40 piston reciprocable therein, and a scavenging pump, spaced from said piston, said pump being disposed in axial alignment with the working cylinder and operable therewith, means responsive to movement of the power piston for actuating the pump in a direction opposite to that of the power piston. 45

8. In a two-cycle internal combustion engine, the combination of a working cylinder, a power 50 piston reciprocable therein, and a scavenging pump, said pump confined wholly within the limits of the cylinder block, and means responsive to power piston movement for actuating the pump in a direction opposite to the movement of the power piston.

9. In a two-cycle internal combustion engine, the combination of a working cylinder, a power 55 piston reciprocable therein, and a scavenging pump, spaced from said piston, said pump being disposed in axial alignment with the working cylinder and operable therewith, and means responsive to power piston movement to drive said piston and pump in opposite axial directions.

10. In a two-cycle internal combustion engine, the combination of a working cylinder, a power 60 piston reciprocable therein, and a scavenging pump, said pump confined wholly within the limits of the cylinder block, means responsive to power piston movement for actuating said pump in a direction opposite to the movement 70 of the power piston, the pressure movement of the pump being in a direction away from the working cylinder.

11. In a two-cycle internal combustion engine, the combination of a working cylinder, a power 75

piston reciprocable therein, a fuel injection means, a fuel injection pump, and a scavenging pump, spaced from said piston, said pump being disposed in axial alignment with the working cylinder and operable therewith means to drive said piston and pump in opposite directions on their power strokes, and said fuel injection means operable in a direction opposite that of the power piston.

10 12. In a two-cycle engine, the combination of a working cylinder, a piston mounted for reciprocation therein, a crank shaft, means for connecting the piston and crank shaft, a double acting pump, and means connected with the crank shaft for reciprocating said pump, one side of said pump adapted to scavenge the burnt gases from the working cylinder while the other side of said pump is adapted to prepare a charge of fuel for injection into said working cylinder.

15 13. The method of operating two-cycle engines consisting in forming a rich fuel mixture in a gas such as air, expanding said mixture in a partial vacuum, simultaneously scavenging burnt gases of the previous explosion, and finally compressing and injecting said mixture of fuel into air under pressure approximating the maximum compression of the engine.

20 14. The method of operating two-cycle engines consisting in forming a rich fuel mixture in a gas such as air, expanding said mixture in a partial vacuum, simultaneously scavenging burnt gases of the previous explosion, compressing said mixture containing the vaporized fuel, and delivering the compressed fuel mixture into compressed air whose pressure is less than that of said fuel mixture but approximates the maximum compression of the engine.

25 15. The method of operating two-cycle engines consisting in forming a measured quantity of rich fuel mixture in a gas such as air, expanding said mixture in a partial vacuum, simultaneously scavenging burnt gases of a previous combustion in the engine, and finally compressing and injecting said fuel charge into air under pressure approximating the maximum compression of the engine.

30 16. The method of operating two-cycle engines consisting in forming a rich fuel mixture in a gas such as air, expanding said mixture in a partial vacuum, heating the said mixture by the heat produced by the preceding combustions, simultaneously scavenging burnt gases of the previous explosion, compressing said mixture containing the vaporized fuel, and delivering the compressed fuel mixture into compressed air whose pressure is less than that of said fuel mixture but approximates the maximum compression of the engine.

35 17. The method of operating two-cycle internal combustion engines which includes during the compression stroke of air in a closed chamber, compressing to a high degree of a charge of a rich mixture of fuel in a closed relatively small chamber, sucking into a third closed chamber a quantity of scavenging air, injecting the charge of fuel into the combustion chamber when the combustion air contained therein is compressed substantially to a maximum to cause complete combustion of the fuel and finally driving out the burnt gases from the first chamber and sucking in a charge of richly mixed fuel to the second mentioned chamber simultaneously.

40 18. In a two cycle engine, in combination, a cylinder block, a crank shaft, a working cylinder having a working piston, a fuel mixing cylinder

45 and a scavenging air compression cylinder in spaced relation but in axial alignment confined in said block, a double acting pump having oppositely disposed piston portions working in said fuel mixing and air compression cylinders, a valve 5 between the fuel mixing and working cylinders, a connection between the air compression cylinder and working cylinder and eccentric means for connecting said double acting pump to said crank shaft to cause said pump to move opposite 10 to said working piston and in timed relation therewith.

15 19. In a two-cycle internal combustion engine, the combination of a working cylinder, a power piston operable therein, a scavenging pump disposed in axial alignment with the cylinder and wholly independent of the working cylinder and power piston, and operating connections to compel a suction movement of the pump during a compressing movement of the power piston and a 20 power movement of the pump during a scavenging movement of the power piston, a communication between said pump and said cylinder normally closed against the cylinder and means for opening said communication to establish communication between the pump and cylinder when the power piston has reached its 25 scavenging limit position.

20 20. In a two-cycle internal combustion engine, the combination of a working cylinder, a power 30 piston operable therein, a scavenging pump confined wholly within the limits of the cylinder block and disposed in axial alignment with the working cylinder and wholly independent of the working cylinder and power piston, and operable 35 connections to compel a suction movement of the pump during a compression movement of the power cylinder and a pressure movement of the pump during a scavenging movement of the power piston, a communication between said pump and 40 said cylinder normally closed against the cylinder and means for opening said communication to establish communication between the pump and cylinder when the power piston has reached its 45 scavenging limit position.

25 21. In a two-cycle internal combustion engine, the combination of a working cylinder, a power piston reciprocable therein, a scavenging pump confined wholly within the limits of the cylinder block and in axial alignment with the cylinder 50 and wholly independent of the working cylinder and power piston, and means for driving the pump in opposition to and in timed relation with the movement of the piston whereby a suction movement of the pump is effected during a compression movement of the power piston and a power movement of the pump is effected during a scavenging movement of the power piston, to normally close communication between the pump and cylinder, and means incident to pressure in 55 the pump for opening said communication in the scavenging limit position of the power piston.

60 22. In a two-cycle internal combustion engine, the combination of a working cylinder, a power piston reciprocable therein, a scavenging pump 65 spaced from the cylinder and disposed in axial alignment with the working cylinder and wholly independent of the working cylinder and power piston, a communication between said pump and working cylinder, said communication being 70 maintained closed by the pressure of the working piston except at the limit of the scavenging stroke of said piston, the pressure of the pump operating to open said communication at the limit of the scavenging stroke of the power piston, and oper- 75

able connections timing the power piston and pump to compel a suction movement of the pump in a compression movement of the power piston and a power movement of the pump during the 5 scavenging stroke of the power piston.

23. In a two-cycle internal combustion engine, the combination of a working cylinder, a power piston reciprocable therein, a scavenging pump confined wholly within the limits of the cylinder 10 block and disposed in axial alignment with the cylinder and wholly independent of the working cylinder and power piston, and means whereby the movement of the power piston is communicated to the pump, said means compelling the

pump to move on a suction stroke in the compression movement of the power piston and compelling the pump to move on a power stroke during the scavenging movement of the power piston, said pump having a path of communication with the cylinder, and means responsive to pressure in the working cylinder to maintain said communication closed during operation of the power piston, said means responding to pump pressure at the limit of the scavenging stroke of the power 10 piston to open said communication. 5
